MICHAEL B. FIELD AND DONALD RENFREW, OF GLASGOW, SCOTLAND.

MARINER'S COMPASS.

1,110,318.

Specification of Letters Patent. Patented Sept. 15, 1914.

Application filed January 5, 1914. Serial No. 810,486.

To all whom it may concern:

Be it known that we, MICHAEL BIRT FIELD and DONALD RENFREW, subjects of the King of the United Kingdom of Great Britain and Ireland, both residing at 16, 18, and 20 Cambridge street, Glasgow, Scotland, have invented a certain new and useful Improvement in Mariners' Compasses, of which the following is a specification.

The primary object of the present invention is to provide as an adjunct to a mariner's compass an optical system adapted to be supported independently of the compass bowl, and capable of use when the binnacle hood is in place though not liable to interfere with the convenient removability of said hood, the said optical system being adapted to present an image, in a plane approximately normal to the line of sight, of the lubber point and of a substantial segment of the compass card, in such a manner that, while the helmsman can read the card graduations in the neighborhood of the lubber point to a nicety, he is able to determine the general orientation of the card, these results being obtained in a more effective manner than has been possible by any of the various arrangements proposed heretofore.

Other objects will appear from the following description.

In the accompanying drawings, Figure 1 is a longitudinal vertical section of a binnacle top equipped with an optical system designed to realize the objects of the invention; Figs. 2 and 3 show modifications; Fig. 4 shows part of a compass card which has no reversed markings and which may be employed in a compass equipped with the said optical system; Figs. 5 and 6 show typical images presented to the observer by the optical system.

Referring to Fig. 1, the optical system shown comprises a lens 1 and two reflectors, in the particular instance two mirrors 2 and 3, either or both of which may be angularly adjustable, said system being mounted independently of the compass bowl 4 in which are contained the horizontally disposed lubber mark 5 and card 6. The lens 1 receives rays which leave the card 6 on its upper side. The mirror 2 in turn receives the rays from the lens 1 and reflects them on to the mirror 3 whence they pass to the eye of the observer; said mirror 3 being located in a plane inclined to the vertical. With this arrangement the image presented to the

observer's eye will appear as the representation of a substantial segment of the compass card 6 and of the lubber mark 5 standing in an approximately vertical plane and disposed in relation to one another in the same way as the actual lubber mark 5 is disposed in relation to the actual card 6 as viewed when steering directly from the card, so that the helmsman will have no sense of awkwardness in steering with the combination of compass and optical system.

As will be understood, with the employment of the optical system shown it is possible to employ a card without reversed markings of any description, so that the card may be simplified, and the points of the card brought near to the periphery so as to be visible with the cardinal, quadrantal and other letterings on the magnified image. It is thus possible to avoid liability to confusion when the card is being read direct, or read in conjunction with an azimuth mirror.

The mirror 2 is located so as not to obstruct the view of the observer looking approximately horizontally into the mirror 3, e.g., it may be located at a higher level than the mirror 3 and disposed at an inclination to the horizontal within a darkened chamber 7 in optical communication with the interior of the removable hood or helmet 8.

The interior of the hood 8 up to the aperture opening into the darkened chamber 7 is painted white to provide greater illumination of the compass bowl and card, and at the lubber mark side of the hood is a glazed aperture 9 provided with an adjustable cover plate 9^a adapted to permit daylight to be thrown on the card from the lubber mark side, the hood being also provided with an inspection aperture 10 serving to permit a full view of the card from the helmsman's position when situated near the binnacle. The chamber 7 is painted black so as to absorb any stray light and as far as possible to confine the illumination to what passes through the lens 1 on to the mirror 2.

The lens 1 and mirrors 2 and 3 are preferably of rectangular form or of the form represented by the image shown in Fig. 5 and are so disposed in the chamber 7 that the helmsman looking into said chamber 7 will see the image of part of the card and the lubber mark as a detached picture lying in a vertical or approximately vertical plane and not necessarily embraced by a frame and quite independent of the view of the

complete card as seen through the inspection aperture. As a protection against reflections the lens 1 is sunk in a tube 11 leading to the chamber 7. An inclined glass 13 is also placed in front of the mirrors 2 and 3 and sunk within a darkened casing 12, the glass 13 serving as a protection against ingress of spray, dust etc., and the under-face of said casing 12 being inclined so that water etc., will not collect therein.

It will be appreciated that on removal of the hood 8 the optical system is removed at the same time, thereby leaving the bowl 4 free for the fitting thereupon of an azimuth mirror or shadow-pin device for the purpose of taking bearings.

The compass may be artificially lit from below the card or from the side.

In the modification illustrated in Fig. 2 the mirror 3^x viewed by the observer is located external to the binnacle, and may be fixed above the binnacle, being provided with a deep shade, this arrangement being equivalent to division of the darkened chamber 7 into two compartments.

As shown in Fig. 2, the lubber mark 5 is so disposed relatively to the lens that the rays leaving the lubber mark 5 and falling on the lens and mirror 2^x are approximately normal to the lubber mark.

In the form illustrated in Fig. 3 the optical system employed includes a lens 1^y and a single mirror 23, said lens and mirror being located in a darkened chamber similar to that provided in the form first above described. Obviously the image viewed by the observer in the mirror 23 will be the reverse of the card, rendering it necessary or desirable to provide the card with reversed markings.

It will be understood that the constructions above described permit of the use of magnifying means of such focal length as to be capable of being placed sufficiently remote from the card that, while sufficient magnification is insured, the degree of magnification and clearness of the image will not be appreciably affected by any relative motion between the bowl and the binnacle which is likely to occur in practice.

It is an important advantage of the present invention that it provides for the presentation of an image of such a substantial segment of the card as will fully satisfy requirements without sacrifice of compactness, whereas with arrangements supported by the compass bowl which is mounted on gimbals the use of reflectors of sufficient dimensions would be impracticable. An image such as is represented in Figs. 5 and 6 being presented to the helmsman as located in a vertical or approximately vertical plane, may be read by the helmsman without difficulty even when at a distance greater than was previously feasible. In practice

it is found possible for an observer to read the card to a degree even when stationed ten or twelve feet from the binnacle, whereas, to read a horizontally disposed card, the observer must be fairly near to the card itself, because it cannot be read advantageously when the line of sight is but slightly inclined to the plane of the card.

It will be observed that the optical system employed dispenses with the use of a screen on which an image is projected as in compasses of the projector type, the magnifier employed being used practically in the same way as a reading glass, that is, in general, the focal length of the magnifier

70

being greater than its distance from the object to be magnified. Provided the card receives sufficient illumination, whether that of daylight or artificially produced, the image will be sufficiently illuminated: the present arrangement is thus further differentiated from the optical arrangements employed with compasses of the projector type which require the use of a transparent card through which the light is transmitted.

80

While we have described the forms of construction preferred, it will be understood that the details may be widely varied without departure from the spirit of the invention.

85

What we claim is:—

1. The combination with a mariner's compass comprising a bowl containing a card and a lubber mark, of a removable hood surmounting the bowl, a darkened chamber in optical communication with the interior of said hood and an optical system including magnifying and reflecting means for presenting to the observer looking into said chamber an image of said lubber mark and part of said card.

90

2. The combination with a mariner's compass comprising a bowl containing a card and a lubber mark of a removable binnacle hood surmounting the bowl, a darkened chamber having an aperture, said chamber being sustained by said hood and in optical communication with the interior of said hood, and an optical system including magnifying and reflecting means for presentation of an image of part of said card, said image being visible through said aperture.

95

3. In combination with a mariner's compass comprising a bowl containing a card and a lubber mark, a binnacle hood having an aperture for inspection of the lubber mark and the entire compass card, a darkened chamber in optical communication with the interior of the said hood, said chamber having an aperture, and an optical system including reflecting means within said chamber for reflecting through said aperture an image of the lubber mark and part of the compass card.

100

4. In combination with a mariner's com-

105

110

115

120

125

130

pass comprising a bowl containing a card, a closure for the upper end of said bowl, said closure including two chambers the wall of one of which is light and the wall of the other of which chambers is dark, said chambers being in optical communication with one another, and said second chamber having an aperture, and optical devices for presenting an image visible through said 10 aperture of part of said card.

5. The combination with a compass binnacle hood having an aperture for inspection of the compass card, of a chamber supported by said hood, said chamber having 15 an aperture, and an optical system including magnifying and reflecting means, said reflecting means being contained within said chamber and adapted to present an image of part of said card, said image being visible 20 through the aperture in said chamber.

6. The combination with a mariner's compass comprising a bowl containing a card and a lubber mark, of a removable binnacle hood surmounting the bowl, a chamber hav-

ing an aperture, said chamber being sustained by and in optical communication with said hood, and an optical system including a reflector within said chamber for presenting an image of part of said card, said image being visible through said aperture. 25 30

7. The combination with a mariner's compass comprising a bowl containing a card, of a binnacle hood surmounting the bowl, a darkened chamber having an aperture, said 35 chamber being in optical communication with the interior of said hood, and two reflectors within said chamber for receiving and reflecting through said aperture an image of part of said card. 40

In testimony whereof we have signed our names to this specification in the presence of two subscribing witnesses.
